UNITED STATES PATENT OFFICE

149,731

DESIGN FOR A HOOD FOR A POWER
ROTARY MOWER

Perry Belden, Lansdale, Pa., assignor to Roto-mower, Inc., Lansdale, Pa., a corporation of Pennsylvania

Application May 15, 1946, Serial No. 129,730

Term of patent 7 years

(Cl. D40—1)

To all whom it may concern:

Be it known that I, Perry Belden, a citizen of the United States, residing in Lansdale, county of Montgomery, in the State of Pennsylvania, have invented a new, original, and ornamental Design for a Hood for a Power Rotary Mower, of which the following is a specification, reference being had to the accompanying drawings, forming part thereof.

Fig. 1 is a top plan view of a hood for a power rotary mower showing my new design.

Fig. 2 is a true perspective as seen from the rear and slightly above the cover;

Fig. 3 is a front elevation;

Fig. 4 is a right side elevation; and

Fig. 5 is a sectional elevation taken substantially along the line 5—5 of Fig. 1.

I claim:

The ornamental design for a hood for a power rotary mower, as shown.

PERRY BELDEN.
